UNITED STATES PATENT OFFICE.

PHILIP HENRY WYNNE, OF BOSTON, MASSACHUSETTS, ASSIGNOR, BY
MESNE ASSIGNMENTS, TO HUFF ELECTROSTATIC SEPARATOR COM-
PANY, A CORPORATION OF MAINE.

ELECTROSTATIC SEPARATOR.

No. 840,815.

Specification of Letters Patent.

Patented Jan. 8, 1907.

Application filed January 20, 1905. Serial No. 241,981.

To all whom it may concern:

Be it known that I, PHILIP HENRY WYNNE, a citizen of the United States, and a resident of Boston, in the county of Suffolk and State 5 of Massachusetts, have invented new and useful Improvements in Electrostatic Separators, of which the following is a specification.

My invention relates to the art of electrostatic separation, concentration, or classification 10 of the components of heterogeneous mixtures of solid material—such as, for instance, metallic ores and the gangues wherewith they are mixed; and it consists in improved apparatus whereby the application of 15 static electricity to the components of such mixtures is regulated with respect to the time period of said application.

As elaborated in an application for Letters Patent of the United States heretofore filed 20 by me on or about August 2, 1904, Serial No. 219,240, for an improved method of electrostatic separation, it had been observed that the unregulated application of potential to the electrodes of an electrostatic separator re- 25 sulted in the communication of the charge to more than one component of a mixture, so that the attempted classification according to conductivities was very largely defeated, as many substances which under other condi- 30 tions might be separately classed as "conductors" and "non-conductors" behaved under the said conditions of electrostatic separation with unregulated potential, alike as conductors. The process described in my said ap- 35 plication is characterized by the regulation in respect to time of the application of the static charge at the electrodes of a separator to the materials to be separated or classified. I had discovered that although many sub- 40 stances are, under conditions of continu- ously-applied potential, similarly conductors of electricity, the differences in degree be- 45 tween their conductivities is manifested by differences in the elapsed times required for them to assume the potential of the body wherewith they are brought into effective contact for the purpose of receiving the separative electrification. Therefore by reduc- 50 ing the time duration of the potential applied to the charging-body I was enabled to differentiate between substances which under conditions of substantially continuous potential exhibited no sufficient distinction.

The subject of the present specification is an improvement in apparatus for electrostatic separation; and it consists in its preferred form of the separator-electrodes, a source of potential, and connections between the source and the electrodes, which comprise means for interrupting the communication of potential from the source to the electrodes or for regulating the duration of each such communication of potential. My invention may, however, be carried out and embodied in an apparatus which, in connection with the electrodes of a static separator, comprises a source of potential of which the structure and mode of operation in itself involve the communication of effective potential intermittently to the electrodes. 70

Under the conditions of fine comminution of materials to be treated and the high potentials which have been found most adequate effectively to separate by repulsion conductive particles of a comminuted mass 75 the time actually required to charge a conductor by effective contact with an electrode is so extremely short that potential whereof the fluctuations would ordinarily be considered very rapid nevertheless acts as if it 80 were practically continuous in relation to the said time periods of charge for comminuted matter. It must be borne in mind, therefore, that the definitive terms used herein are referable to those conditions which are 85 peculiar to electrostatic separation and that it may well be, for instance, that the potential derived from an alternating-current generator may, unless the transmission of potential to the separate electrodes is specifically regulated, produce at each alternation 90 in phase a potential which, in effect, is continuous, although apparently and according to ordinary standards it is very rapidly alter- 95

In the drawings hereto annexed, Figure 1 illustrates diagrammatically and partly in perspective a form in which my invention may be embodied. Fig. 2 illustrates diagrammatically the interrupter or commutator 100 which forms a component part of the apparatus shown in Fig. 1. Fig. 3 shows diagrammatically and partly in perspective another form of apparatus embodying my invention, and Fig. 4 shows in skeleton form 105 and diagrammatically a specific form of in-

terrupter or commutator which is a component of the apparatus shown in Fig. 3.

In Fig. 1, R represents a cylinder composed of hard rubber or other good insulating material, the said cylinder mounted upon a shaft, as at R'. P P' represent the terminals of a generator of potential—say, in this case, an electrostatic influence or friction machine. E E' represent the two electrodes of an electrostatic separator whereof the electrode E (shown in cross-section) is a rotating cylinder having an electroconductive surface and the electrode E' is a wire surrounded, preferably, by an insulating envelop. A hopper H above the electrodes contains and delivers the mixed material which falls upon the surface of the rotating electrode E, and between the electrodes E E' there is mounted a divider D, of insulating material. The terminals P P' are connected with the electrodes E E' by means of the wires 1 2 17 18, the brushes 3 4 19 20, and the interrupter, which is contained and carried by the cylinder R, presently to be described.

Reference to Fig. 2 will enable the construction of the interrupter to be more clearly understood. In Fig. 2 the surface of the cylinder R is shown as developed. Upon the surface of the insulating material of which the cylinder is composed there are secured contact-strips *a b a' b'* and *c d c' d'* and likewise the discharging-plates M N. Strip *a* is connected to strip *a'*, strip *b* to *b'*, strip *c* to strip *d'*, and strip *d* to strip *c'*. The brushes 3 4 19 20 are mounted so as to make contact with the strips *a b a' b'* and *c d d' c'* as the cylinder R (Fig. 1) rotates in the direction of the curved arrow. As will be seen from examination of Fig. 2, when the strips *a b a' b'* are in contact with the brushes, then electrode E is in connection with negative pole P' and the electrode E' with the positive pole P. When the relation of the cylinder R carries these strips out from under the brushes, the electrodes E E' would remain charged until the second set of strips came in contact with the brushes were it not for the discharging-plate M, into contact with which the two brushes 19 20 immediately come in the rotation of the cylinder R, and the electrodes E E' are consequently discharged. Then in the rotation of the cylinder there follows an interval of no excitation for the electrodes E E' until the strips *c d d' c'* make contact with the brushes 3 4 19 20. The connections are now such that electrode E is connected with pole P and electrode E' with pole P'. Again, as the rotation of the cylinder continues the brushes 19 20, coming in contact with the discharging-plate N, discharge the electrodes E E'.

By the above arrangement the duration of successive potential impulses at the electrodes E E' may be regulated. The strips *a b a' b' c d c' d'* may be made long or short at will; or, if desired, the pairs of brushes 3 4 19

20 can be so mounted that one pair has a desired lead over the other, so that the interval within which all four brushes are in contact with the strips may be quite finely adjusted.

Figs. 3 and 4 illustrate another specific form and embodiment of my invention. As before, P P' represent the terminals of an electrostatic machine, and E E' the electrodes of the electrostatic separator. The wires 1 2 lead from the terminals of the source of potential to brushes 3 4 and the wires 17 18 to brushes 19 20, these brushes bearing the same relation electrically to the apparatus as do the terminals similarly numbered in Fig. 1. Upon the shaft S there are mounted 80 wooden disks X Y, to which are secured segmental contact-pieces *a b c d a' b' c' d'*, respectively. These segmental contact-pieces are symmetrically arranged and are concentric with the axis of the shaft S. They are also so 85 angularly disposed with relation to the shaft that the segments *a b a' b'* lie between the same radial planes, as also do the segments *c d c' d'*. Referring now to Fig. 4, the connection between these segments may be made 90 plainer. The outer segment *a* is wired directly to the outer segment *a'* and the inner segment *b* to the inner segment *b'*. On the other side the outer segment *c* is wired to the inner segment *d'* and the inner segment *d* to 95 the outer segment *c'*. The brushes 3 4 19 20 are mounted so as to make contact with the segmental contact-pieces on the two disks X Y. Upon the rotation of the shaft S in the direction indicated by the arrow the connections between the source of potential P P' and the separator-electrodes E E' are established and broken recurrently. When, as in Fig. 3, the brushes 3 4 19 20 are in contact, respectively, with segmental contact-pieces *a b* 100 *b' a'*, electrode E will be negatively and electrode E' positively charged. When in the course of rotation of the shaft S brushes 3 4 19 20 are brought into contact with the segments *c d d' c'*, respectively, by means of the cross-connections shown in Fig. 4, the electrode E will be excited positively and the electrode E' negatively. With the wooden disks X Y special discharging arrangements, like the plates M N of Figs. 1 and 2, are not 105 always necessary, for the reason that the wood of which the disks are composed is often sufficiently conductive to discharge the electrodes E E' through the brushes 19 and 20, provided the supply from the terminals P P' be not 110 kept up, as is the case when brushes 3 4 have left the contact-strips on the disk X. When all four brushes are in contact with the strips, while there is some leakage through the wood of the disks this is overcome by the supply 115 from the generative source whereof the poles are P P'. The time limit of excitation of the electrodes E E' of the separator depends with this apparatus upon the speed of rotation of the shaft S and the angular extent of the seg- 120 125 130

mental contact-pieces $a b c d a' b' c' d'$, and by means of these two factors the potential duration at the separator-electrodes may be regulated. If it be desired to excite the electrodes E E' intermittently without change of polarity, one pair of the interrupter connections may be eliminated by omitting or covering one set of segmental contact-pieces, such as shown in Fig. 3.

10 What I claim, and desire to secure by Letters Patent, is—

1. The combination with the electrodes of an electrostatic separator, of means to supply potential to the electrodes at intervals, and means to deprive the electrodes of potential in the intervals between the acts of supply.

2. In an electrostatic separator, the combination with the electrodes, of a source of potential, connections between the source and the electrodes, and means interposed between the electrodes and the said source substantially to deprive the electrodes of potential except during predetermined intervals of time.

25 3. In an electrostatic separator, the combination with the electrodes, of a source of

potential, connections between the source and the electrodes, and means to interrupt recurrently the persistence of effective potential on the electrodes.

30

4. In an electrostatic separator, the combination with the electrodes, of a source of potential, connections between the source and the electrodes, comprising a rotary interrupter, recurrently to deprive the electrodes of potential.

35

5. In an electrostatic separator, the combination with the electrodes, of a source of potential, connections between the source and the electrodes, comprising segmental 40 contact-pieces, brushes therefor, and means relatively to move the brushes and segmental contact-pieces in order recurrently and alternately to supply the electrodes with potential from the source and to deprive the electrodes of potential.

45

Signed by me at Boston, Massachusetts, this 10th day of January, 1905.

PHILIP HENRY WYNNE.
